UNITED STATES PATENT OFFICE.

JOSEPH W. EDGERTON, OF GRAND ISLAND, NEBRASKA.

HOOK AND EYE.

SPECIFICATION forming part of Letters Patent No. 726,888, dated May 5, 1903.

Application filed October 11, 1902. Serial No. 126,889. (No model.)

To all whom it may concern:

Be it known that I, JOSEPH W. EDGERTON, a citizen of the United States, residing at Grand Island, in the county of Hall and State 5 of Nebraska, have invented a new and useful Hook and Eye, of which the following is a specification.

This invention relates to hooks and eyes.

The object of the invention is to present a 10 hook and eye in which the parts may readily and without difficulty be engaged and disengaged and which when engaged will be positively held against disconnection no matter what position may be assumed by the body 15 of the wearer.

The hook and eye of the present invention is comparatively flat and may be used in connection with tight-fitting garments without pressing into the flesh or producing raised 20 portions of the garment, which are unsightly and soon become threadbare. When used in connection with loose-fitting garments, the elements cannot become accidentally disengaged no matter at what angle the complementary 25 parts may be turned, the fastening as a whole being strong and durable and of such construction that those portions subject to and receiving the greatest wear and strain are reinforced and interlocked at those points.

With the above-stated and other objects in view, as will appear as the nature of the invention is better understood, the same consists in the novel construction and combination of parts of a hook and eye, as will be 35 hereinafter fully described and claimed.

In the accompanying drawings, forming a part of this specification and in which like numerals of reference indicate corresponding parts, there are illustrated two forms of embodiment of invention, each capable of carrying the same into practical operation, it being understood that the elements therein exhibited may be varied or changed as to shape, proportion, and exact manner of assemblage 45 without departing from the spirit thereof, and in these drawings—

Figure 1 is a view in perspective of one form of embodiment of the invention, showing the position of the parts when they are 50 in locked engagement with each other. Fig. 2 is a similar view showing the position assumed by the members of the hook when the

hook and eye are to be disconnected. Fig. 3 is an edge view. Fig. 4 is a view in plan of a slightly-modified form of construction. 55

Referring to the drawings and to Figs. 1, 2, and 3 thereof, 1 designates generally the hook, and 2 the eye. The hook is constructed of a single piece of metal, preferably of wire, the free terminals of which are bent to form attaching-loops 3, which may be circular, as shown, or otherwise contoured. The wire adjacent to the loops is bent outward to form outward shoulders or projections 4, thence bent inward toward each other, as at 55 5, thence downward and outward to present eye-engaging bends 6, thence inward at converging angles to present lateral jaws 7, disposed beneath and approximately of the same contour as the shoulders 4, thence forward approximately parallel with each other to present bills 8, thence rearward to present eye-engaging bends or loops 9, and thence into a tongue comprising two members 10, terminating in a bend 11, constituting 75 a securing-loop.

The eye 2 is constructed with a straight nose 12, terminating in rounded terminals 13, the side members of the eye being bent to converge toward the other and then formed 80 into attaching-loops 14.

When the hook and eye are in locked engagement, as shown in Fig. 1, the bends 6 engage the bends 13 of the nose and the jaws 7 project laterally beyond the end bends 85 13, so that any movement toward each other of the members will not result in their accidental disconnection, as they will be positively locked thereagainst. To facilitate interlocking of the bills with the nose, the latter is upturned, as shown at 15 in Fig. 3, and to insure a stable connection between the parts and to reduce liability of accidental separation in use to a minimum the terminals of the bills are upturned, as shown at 90 16 in Fig. 3. By this arrangement it will be seen that not only is the proper operative connection between the parts secured, but by the upturning of the nose, and the bills the structure is rendered practically flat, so that 100 it will not press into the flesh of the user, with resulting discomfort, nor will it cause portions of the garment to protrude, and thus rapidly become threadbare. The upturned

terminals of the nose-engaging bills being connected by the intermediate members 10 11, as shown in Figs. 1 and 2, greatly strengthens the structure of the hook.

5 In the form of embodiment of the invention shown in Fig. 4 the eye is constructed in the same manner as that shown in Figs. 1 and 3. There is a difference, however, in the construction of the hook, the same underlying principle, however, being common to both. In the latter form of embodiment of the invention the bends 9 are dispensed with, and the terminals of the wire are bent over against the sides of the jaws 17, as shown at 18. When 15 the hook is constructed in this manner, the attaching-loops 19 do not terminate with the shanks 20 of the jaw-carrying member, but are connected by a length of wire 21, disposed beneath the two members 20.

20 In engaging the hook with the eye it will be only necessary to introduce the bills over the nose and draw on the hook, when the angular sides of the jaws by contacting with the bends 13 of the eye will cause the jaws 25 to be projected toward each other, and thus enter the hook, after which they spring laterally to interlock the bends 6 with the bends 13. To disconnect the hook and eye, the elements may be separated by simply bending 30 inward at the terminal of each one; but where the garment is tight-fitting this will be impractical, and to obviate this the shoulders 4 are provided to be engaged by the fingers to effect compression of the jaws, as shown in 35 Fig. 2, thus to permit of their disconnection from the hook.

The device of this invention is exceedingly simple in construction, may be readily manufactured, and will be found in a simple and 40 practical manner to obviate many defects heretofore inherent in devices of this character.

Having thus described the invention, what I claim is—

1. A garment-fastener comprising an eye 45 having attaching-loops and a straight upturned nose provided with bent terminals, and a hook having terminal attaching-loops, undeturned nose-engaging bills provided with upturned terminals, and lateral jaws to interlock with and project beyond the terminals of the nose.

2. A garment-fastening comprising an eye 55 having attaching-loops and an upturned nose, and a hook having attaching-loops, nose-engaging bills provided with connected upturned terminals, and lateral jaws to interlock with and project beyond the terminals of the nose.

3. A garment-fastener comprising an eye 60 having attaching-loops and a straight upturned nose provided with bent terminals, a hook having attaching-loops, lateral shoulders, undeturned upward-curved bills to engage the nose, and lateral jaws to interlock 65 with and project beyond the terminals of the nose.

4. A garment-fastener comprising an eye having attaching-loops and a straight upturned nose provided with bent terminals, and 70 a hook having undeturned bills to engage the nose and lateral jaws to interlock with and project beyond the terminals of said nose, the inner members of the bills being bent upon themselves to constitute loops and 75 thence carried to the rear of the hook and formed into an attaching-loop.

In testimony that I claim the foregoing as my own I have hereto affixed my signature in the presence of two witnesses.

JOSEPH W. EDGERTON.
